UNITED STATES PATENT OFFICE.

HAROLD FRANK WOODMAN, OF CROYDON, ENGLAND, ASSIGNOR TO HAROLD FRANK WOODMAN AND CREED & CO., LIMITED, OF CROYDON, SURREY, ENGLAND.

ELECTRIC-CIRCUIT-CONTROLLING MEANS.

Application filed December 16, 1925. Serial No. 75,838.

To all whom it may concern:

Be it known that I, HAROLD FRANK WOODMAN, a subject of the King of Great Britain and Ireland, residing at Croydon, in the county of Surrey, England, have invented Improvements in or Relating to Electric-Circuit-Controlling Means, of which the following is a specification.

This invention relates to electric circuit controlling means suitable for various purposes where constancy of speed is required for effecting some desired operation, or for producing some desired effect, and specially suitable for the interpolation or resolution of cable code signals or other signals, for example those of multiple unit systems, that have been caused to lose their individuality and assume the form of block signals, owing, for instance, to the capacity of the transmitting cable or line.

Interpolators as at present employed, depend usually for their constancy of speed upon two uncertain factors. The first, is the bias adjustment of one or more relays which, in most instances, is not absolutely constant. The second factor is the dependence upon excellence of contact at relay contact points, for the frequency of oscillation. If this contact is imperfect, resistance is introduced into the circuit which alters the speed of vibration of a circuit making and breaking device.

An object of the present invention is to provide improved electric circuit controlling means devoid of the aforesaid uncertainties and which can be adjusted to allow of the desired speed of a circuit making and breaking device being set with less trouble than has heretofore been possible.

For this purpose, in electric circuit controlling means according to the invention, a circuit making and breaking device arranged to open and close an electric circuit or circuits is adapted to be oscillated by the combined action of two mutually inductive coils one of which is included in the anode circuit of a thermionic valve provided with a switch for opening and closing such circuit, and the other of which is included in or controlled by the grid circuit of the valve and is adapted to be tuned in order that the said circuit making and breaking device may be oscillated at any desired frequency dependent solely upon the characteristics of the associated circuits.

Such electric circuit controlling means can be adapted for various uses. Thus, in the case of an interpolator for the interpolation or resolution of cable code or other signals, the cable or other signals received are caused to influence a relay tongue or switch that selectively brings into use, according to the nature of the signal received, one or other of two thermionic valves each of which is associated with circuits that include the coils of a corresponding electro-mechanical device or relay adapted to transfer to a second circuit or circuits, electric signals corresponding in phase relationship to the oscillations which are set up with the aid of the coils aforesaid. For controlling other circuits, a single thermionic valve with associated coils and a single electro-mechanically operated device may be used.

In the accompanying illustrative drawings, Figs. 1, 2 and 3 show diagrammatically, three arrangements of electric circuit controlling means according to the invention suitable for three different uses.

In Fig. 1, which shows an interpolator embodying the invention, the positive pole of a high tension battery 1 is connected to the tongue or switch 2 of a receiving relay 3 in the line circuit L E, the contact pins 4, 4^a associated with the said tongue or switch 2, being respectively connected to the anodes 5, 6 of two three-electrode vacuum valves. A high resistance 7 or 7^a preferably shunts each contact pin 4, 4^a and the tongue or switch 2, so as to eliminate sparking and reduce the possibility of the tongue or switch sticking to the pins. The filament 8 or 9 of each valve is connected directly to the junction of the filament battery 10 with the anode battery 1 and also to the negative pole of the filament battery 10 through a variable resistance 11 or 12. The grid 13 or 14 of each valve is connected through a variable condenser 15 or 15^a and coil 16 or 17, in parallel, to the negative pole of the filament battery 10. The said coil 16 or 17 is wound to a high impedance and is so associated with a second coil 18 or 19, also of high impedance, included in the anode circuit, that there is mutual high inductance between the coils. The coils 16 and 18 constitute part of a relay A and influence an armature 20 that is adapted to vibrate between two contacts 22, 23 of a repeating circuit across which is connected a battery 26.

The coils 17 and 19 constitute part of a second relay B and influence an armature 21 adapted to vibrate between two contacts 24, 25 of the repeater circuit connected 5 across the same battery 26. Each armature has or may have a bias which can be readily adjusted in known way to enable the time relationship between marking and spacing periods to be varied without altering its 10 speed of vibration, which can itself be determined by adjusting the condenser 15 or 15^a. Each condenser need only be of small capacity capable of being varied to suit requirement. The whole arrangement is one 15 whereby, given appropriate values of inductance for the coils 16—18 and 17—19, sufficient mutual inductance between such coils and appropriate values of filament current and plate voltage, sustained oscillations 20 will be set up in the corresponding tuned circuit when the anode circuit is closed by the tongue or switch 2, the frequency of such oscillations being dependent on the inductance of the coils 16 or 17 and capacity 25 of the condenser 15 or 15^a of such circuit.

It will thus be appreciated that the speed of oscillation is dependent on quantities which are or can be made constant.

If the filament voltage and current 30 through each valve be set at a definite value and the voltage on the anode 5 or 6 be maintained practically constant, each condenser scale can be calibrated for any particular value, and thus the speed of the corresponding armature can be set without any lengthy speed tests such as are ordinarily necessary.

In operation, as soon as a dot impulse, or 40 a series of dot impulses, is received, the tongue or switch 2 of the relay 3 short circuits the resistance 7 or 7^a in the anode circuit of one of the valves, say the resistance 7 in the circuit of the anode 5, the reception of a dash impulse or series of dash impulses similarly short circuiting the other resistance 7^a. In either case, the short circuit of 45 a resistance as referred to, results in the setting up in the corresponding tuned circuit of oscillations or vibrations which are repeated by the armature 20 or 21 of the corresponding relay A or B associated therewith. It is obvious then that if the tongue or switch 2 be held against either of the contacts 4, 4^a for a time equal, or approximately 50 equal, to a definite number of signal time units, that same number of signals will be transmitted by the action of the responding armatures 20 or 21 to a recorder, or to a local or second line and earth, and a true resolution or interpolation made of the signal 55 which caused the tongue or switch 2 to effect the direct closing of the corresponding anode circuit for that definite number of signal time units.

It will be understood that a single thermionic valve with associated coils, tuning con-

denser, batteries, armature and a relay tongue or hand operated or other switch for closing the anode circuit of the valve, all arranged as described can be used for oscillating the armature for opening and closing, at any desired frequency, an electric circuit for various purposes.

Fig. 2 shows diagrammatically one arrangement of the kind just referred to, adapted for controlling the speed of a constant speed motor such as is frequently used in synchronous systems of telegraphy. In this example, the anode circuit of the thermionic valve 5, 8, 13 is arranged to be closed through a hand operated switch 27 and the contact 4, and the armature 20 thereby caused to vibrate at a constant speed, in the manner and by the means hereinbefore described, to open and close, through contacts 22^a and 23^a the circuit of a battery 26^a and an electric motor represented by the field coils 28 and 29 and armature 30, and cause such motor to rotate continuously at a constant speed. The electric motor is obviously capable of driving any device the speed of which is required to be constant, as for example a current distributor suitable for controlling the transmission of multiplex or any other synchronous telegraph signals.

Fig. 3 shows, diagrammatically, an example suitable for controlling the transmission of signals in a sonic frequency telegraph system. In this case, the switch member 27^a may be opened and closed by a Wheatstone transmitter in known way and in accordance with the signals to be transmitted, and the coils 16 and 18 set to cause the armature 20 to vibrate at a multiple of the signal speed, between contacts 22^b and 23^b connected to the positive and negative poles respectively of a split battery 32 earthed at E and thereby cause positive and negative signals to be transmitted to a telegraph line L. Thus it will be understood that in circuit controlling apparatus such as hereinbefore described, the rate of oscillation of current in the anode and grid circuits is independent of the motion of the moving body, namely the armature, which has no natural frequency, and which can be caused to vibrate at any desired frequency dependent only on the inductance, and mutual inductance of the coils and capacity or capacities with which they are tuned.

What I claim is:—

1. Electric circuit controlling means comprising a thermionic valve having an anode, grid and filament, an anode circuit including a high tension battery associated with said anode, a switch for closing and opening said circuit, a grid circuit associated with said grid, a low tension battery connected to said filament and to the anode and grid circuit, a coil arranged in the anode circuit, a second coil arranged in inductive relationship to the

first mentioned coil and associated with the grid circuit, means for tuning the associated coils and circuits, an armature adapted to be oscillated by the impulses set up in said 5 coils when the anode circuit is closed by said switch and an electric circuit adapted to be controlled by oscillation of said armature.

2. Electric circuit controlling means comprising a thermionic valve having an anode, 10 grid and filament, an anode circuit including a high tension battery associated with said anode, a switch for closing and opening said circuit, a grid circuit associated with said grid, a low tension battery connected to said 15 filament and to the anode and grid circuits, a coil arranged in the anode circuit, a second coil arranged in inductive relationship to the first mentioned coil and associated with the grid circuit, means for tuning the associated 20 coils and circuits, an armature adapted to be oscillated by the impulses set up in said coils when the anode circuit is closed by said switch and electric circuits adapted to be controlled by oscillation of said armature.

25 3. Electric circuit controlling means comprising a thermionic valve having an anode, grid and filament, an anode circuit including a high tension battery associated with said anode, a switch for closing and opening said circuit, a grid circuit associated with said grid, a low tension battery connected to said 30 filament and to the anode and grid circuits, a coil arranged in the anode circuit, a second coil arranged in the grid circuit and in inductive relationship to the first mentioned coil, means for tuning the associated coils 35 and circuits to any desired frequency, an armature adapted to be oscillated by the impulses set up in said coils when the anode 40 circuit is closed by said switch and an electric circuit adapted to be controlled by oscillation of said armature.

4. Electric circuit controlling means comprising a thermionic valve having an anode, 45 grid and filament, an anode circuit including a high tension battery associated with said anode, a switch for closing and opening said circuit, a grid circuit associated with said grid, a low tension battery connected to said 50 filament and to the anode and grid circuit, a coil arranged in the anode circuit, a second coil arranged in the grid circuit and in inductive relationship to the first mentioned coil, means for tuning the associated coils 55 and circuits to any desired frequency, an armature adapted to be oscillated by the impulses set up in said coils when the anode circuit is closed by said switch and electric circuits adapted to be controlled by oscillation 60 of said armature.

5. Electric circuit controlling means comprising a thermionic valve having an anode, grid and filament, an anode circuit including a high tension battery associated with said 65 anode, a switch for closing and opening said

circuit, a grid circuit associated with said grid, a low tension battery connected to said filament and to the anode and grid circuits, a coil arranged in the anode circuit, a second coil arranged in the grid circuit and in inductive relationship to the first mentioned coil, an adjustable condenser in parallel with the second coil, an armature adapted to be oscillated by the impulses set up in said coils when the anode circuit is closed by said 70 switch and an electric circuit adapted to be controlled by oscillation of said armature.

6. Electric circuit controlling means comprising a thermionic valve having an anode, grid and filament, an anode circuit including a high tension battery associated with said anode, a switch for closing and opening said circuit, a grid circuit associated with said grid, a low tension battery connected to said filament and to the anode and grid circuits, a coil arranged in the anode circuit, a second coil arranged in the grid circuit and in inductive relationship to the first mentioned coil, an adjustable condenser in parallel with the second coil, an armature adapted to be oscillated by the impulses set up in said coils when the anode circuit is closed by said switch and electric circuits adapted to be controlled by oscillation of said armature.

7. Electric circuit controlling means comprising a thermionic valve having an anode, grid and filament, an anode circuit including a high tension battery associated with said anode, a switch for closing and opening said circuit, a grid circuit associated with said grid, a low tension battery connected to said filament and to the anode and grid circuits, a coil arranged in the anode circuit, a second coil arranged in inductive relationship to the first mentioned coil and associated with the grid circuit, means for tuning the associated coils and circuits, an armature adapted to be oscillated by the impulses set up in said coils when the anode circuit is closed by said switch and an electric impulse transmitting system controlled by oscillation of said armature.

8. Electric circuit controlling means comprising two thermionic valves each having an anode, grid and filament, an anode circuit for each valve, a high tension battery connected to each anode circuit, a coil in each anode circuit, a grid circuit for each valve, a low tension battery connected to each grid circuit and to each filament, a coil associated with each grid circuit, the two coils associated with each valve being arranged in inductive relationship to one another and the anode circuits being connected to the filament circuits, means for tuning the associated coils and circuits of each valve, a receiving relay having its tongue arranged to close the circuits of one

or other of the said anode circuits according as positive or negative signals pass through said relay, an armature associated with each pair of coils and adapted to be 5 oscillated by the impulses set up therein when the corresponding anode circuit is closed by said relay tongue, and electric circuit connections controlled by the respective armatures whereby electric impulses corresponding to the oscillations set up in each pair of coils can be transmitted to a second circuit, the arrangement forming an interpolator.

9. Electric circuit controlling means comprising two thermionic valves each having an anode, grid and filament, an anode circuit for each valve, a high tension battery connected to each anode circuit, a coil in each anode circuit, a grid circuit for each 15 valve, a low tension battery connected to each grid circuit and to each filament, a coil associated with each grid circuit, the two coils associated with each valve being arranged in inductive relationship to one another and the anode circuits being connected to the filament circuits, means for tuning the associated coils and circuits of each valve, a contact connected to each anode circuit, a receiving relay having its 20 tongue arranged to move between the contacts connected to the two anode circuits and close one or other of the said anode circuits accordingly as positive or negative signals pass through the said relay, a high resistance connected between the tongue and each contact, an armature associated with each pair of coils and adapted to be oscillated by the impulses set up therein when the corresponding anode circuit is closed by 25 said relay tongue and electric circuit connections controlled by the respective armatures whereby electric impulses corresponding to the oscillations set up in each pair of coils can be transmitted to a second circuit, the arrangement forming an interpolator.

10. Electric circuit controlling means, comprising two thermionic valves, anode, grid and filament circuits and batteries associated with each valve, a pair of coils 30 associated with the anode and grid circuits respectively of each valve, the two coils corresponding to each valve forming the winding of a relay, a movable armature associated with each pair of coils, means for tuning the associated coils and anode and grid circuits of each valve, a receiving relay the movable tongue of which is adapted to close the anode circuit of one or other 35 of the valves according to the sign of the signals passing through the said line relay, and circuit connections for a repeater circuit controlled by the respective armature and whereby electric oscillations corresponding to the oscillations set up in each pair of

coils and corresponding in sign to the line signals that brought the pairs of coils into action can be transmitted to said repeater circuit.

11. Electric circuit controlling means, 70 comprising two thermionic valves, anode, grid and filament circuits and batteries associated with each valve, a pair of coils associated with the anode and grid circuits respectively of each valve, the two coils 75 corresponding to each valve forming the winding of a relay, a movable armature associated with each pair of coils, means for tuning the associated coils and anode and grid circuits of each valve, a contact connected to each anode circuit, a receiving relay having its tongue arranged to move between the contacts connected to the two anode circuits and close one or other of the said anode circuits according as positive or negative 80 signals pass through the said relay, a high resistance connected between the tongue and each contact, an armature associated with each pair of coils and adapted to be oscillated by the impulses set up therein 85 when the corresponding anode circuit is closed by said relay tongue and electric circuit connections controlled by the respective armatures whereby electric impulses corresponding to the oscillations set up in each pair of coils can be transmitted to a second circuit, the arrangement forming an 90 interpolator.

12. Electric circuit controlling means, 100 comprising two thermionic valves, anode, grid and filament circuits and batteries associated with each valve, a telegraph relay responsive to positive and negative signals passing therethrough, the movable tongue of such relay being adapted to close one or other of the anode circuits according to the sign of the current passing through said relay, a coil in the anode circuit of each valve, a coil in the grid circuit of each valve, the two coils associated with each valve 105 being arranged in inductive relationship to one another, a variable condenser connected in parallel with each grid circuit coil, a movable armature associated with each pair of coils and adapted to be oscillated by the 110 oscillations set up therein when the corresponding anode circuit is closed by said relay and two pairs of stationary contacts for connection to a signal repeater circuit, each armature being arranged to oscillate between one of such pairs of contacts, substantially 115 as described for the purpose set forth.

13. Electric circuit controlling means, 120 comprising two thermionic valves, anode, grid and filament circuits and batteries associated with each valve, a contact connected to each anode circuit, a receiving relay having its tongue arranged to move between the contacts connected to the two anode circuits and close one or other of 125 130

the said anode circuits according as positive or negative signals pass through the said relay, a high resistance connected between the tongue and each contact, a coil in the anode circuit of each valve, a coil in the grid circuit of each valve, the two coils associated with each valve being arranged in inductive relationship to one another, a variable condenser connected in parallel with each grid circuit coil, a movable armature associated with each pair of coils and adapted to be oscillated by the oscillations set up

therein when the corresponding anode circuit is closed by said relay and two pairs of stationary contacts for connection to a signal repeater circuit, each armature being arranged to oscillate between one of such pairs of contacts, substantially as described for the purpose set forth. 15
